(57) **CLAIM**

The ornamental design for a bed sheet retention device as shown and described.

DESCRIPTION

FIG. 1 is a perspective view of a bed sheet retention device showing my new design;

FIG. 2 is a rear view of the bed sheet retention device;
FIG. 3 is a front view of the bed sheet retention device;
FIG. 4 is a right-side view of the bed sheet retention device;
FIG. 5 is a left-side view of the bed sheet retention device;
FIG. 6 is a top view of the bed sheet retention device;
FIG. 7 is a bottom view of the bed sheet retention device;
and,

FIG. 8 is a perspective view of the bed sheet retention device shown in an environment of use.

The dash-dash broken lines shown in the drawings represent environment that form no part of the claimed design.

1 Claim, 8 Drawing Sheets
